[57] CLAIM

The ornamental design for a combined collapsible utility cart and bag therefor, as shown and described.

DESCRIPTION

FIG. 1 is a top and front perspective view of a combined collapsible utility cart and bag therefor showing my new design;

FIG. 2 is a top and front perspective view of collapsible utility cart;

FIG. 3 is a front elevational view of FIG. 2 in collapsed condition;

FIG. 4 is a top and front perspective view of the bag for the utility cart, the rear perspective view being a mirror image of that shown;

FIG. 5 is an enlarged fragmentary inside view of the utility cart leg bottom;

FIG. 6 is a fragmentary outside view of the utility cart leg bottom;

FIG. 7 is an enlarged view of the rotator of the utility cart;

FIG. 8 is an inside view of the rotator;

FIG. 9 is a rear view of the outer rotator member; and

FIG. 10 is a rear view of the inner rotator member.
